UNITED STATES PATENT OFFICE

JAMES A. WHITE, OF LOCKPORT, NEW YORK, ASSIGNOR TO HARRISON RADIATOR CORPORATION, OF LOCKPORT, NEW YORK, A CORPORATION OF NEW YORK

RADIATOR ASSEMBLY

Application filed August 24, 1929. Serial No. 388,086.

This invention relates to radiator structures and particularly to the construction of the general type of radiator that forms a part of the cooling system of an internal combustion engine such as is used on motor vehicles.

As ordinarily constructed, these radiators include a core or heat radiating element and a pair of tanks at opposite ends of the core constituting inlet and outlet headers for the core, and the present invention has to do with a band or hoop to encircle and hold the tanks and core in proper assembled relation and afford a connection with the usual ornamental shell or casing.

One of the objects of the invention is to provide an improved connection between adjacent end portions of the hoop which will eliminate loose parts to be assembled, reduce the number of parts required, simplify manufacture, lessen production costs, facilitate assembly, and insure a positive interlock between the parts.

A further object is to provide an improved connection involving interengaging wedge or cam surfaces movable one on the other to effect the contraction of the hoop tightly about the core and tank assembly.

Additional objects and features of advantage will become apparent during the course of the following specification when taken in connection with the accompanying drawings.

In the drawings:

Fig. 1 is a rear end elevational view of a radiator assembly with the present invention applied thereto.

Fig. 2 is a side elevation of the radiator shown in Fig. 1.

Fig. 3 is a fragmentary detail view of a portion of the structure shown in Fig. 1, on an enlarged scale.

Fig. 4 is a detail perspective view of the interlock between adjacent ears of the strap.

Fig. 5 is a side elevation of the interlock.

Referring to the drawings, the radiator in the present instance, is shown as comprising a pair of spaced inlet and outlet headers 1 and 2 respectively, having interposed therebetween a core or heat radiating element 3

preferably of the well-known cellular formation, comprising a number of preformed plates arranged in spaced pairs to provide water passages connecting the headers with spaces for air flow between the several passages. To hold the core and tanks in proper assembled relation and to also provide an anchorage therefor, it is proposed to surround the core and tank assembly with an encircling hoop or band. This band may comprise a single strap secured together at adjacent ends or a number of straps suitably secured together. In the instant case, the hoop comprises a top portion 5, side portions 6—6, and a bottom portion 7. At the lower end of each side strap 6 there is preferably provided a lateral offset 8 for engagement with the side wall of the tank 2 to space the adjacent portions of the strap and side of the core from each other so that strains and side thrusts in the straps are transmitted to the lower tank 2 rather than on the thin and more delicate metal of the core. The lowermost extremities of the side straps are turned inwardly and are secured as by welding, soldering or the like to the bottom strap 7 so that the bottom and side straps constitute in effect a saddle or U-shaped member which supports the weight of the core in a manner to be later referred to.

The present invention is particularly concerned with the connection between the upper ends of the side straps 6 and the adjacent ends of the top strap 5. The embodiment of the invention as shown in the drawings involves the formation of reversely bent flanges 10 and 11 on the straps 5 and 6 respectively, which provide channeled end portions on the respective straps which open upwardly in one instance, and downwardly in the other, and which oppositely opening channeled portions are adapted for interlocking engagement. The line on which the respective flanges are reversely bent is inclined or diagonally disposed so that there are afforded wedge or cam surfaces which ride one on the other when the two straps are moved laterally relative to each other. The wedging action which takes place during the assembly of the parts because of the inclined cam surfaces, serves to

contract the hoop and draw the straps tightly about the core and tank assembly. This connection eliminates all loose parts such as bolts and nuts, and provides a simple and economical yet very effective and efficient joint. No tools nor special skill are required, and the connection can be effected in a minimum amount of time.

It will be noted that the end portion of 10 the strap 5 at the lower part of the incline is projected laterally beyond the side of the strap 6 to afford a projection or ear 13 which, after the parts are brought into proper wedging relation, may be bent through substantially 90° from the plane of the straps to thereby close the channel formed by the flange 11 and prevent disengagement of the internested parts. For the protection of workmen, sharp edges are eliminated on this tab 20 13 as far as possible, and the corners are rounded. It will be obvious, of course, that in the event it should ever become necessary to disassemble the radiator, the ear 13 may be readily bent back to its original position to open the channel and allow the cam surfaces to be slid off one another.

In addition to holding the tanks and core in assembled relation, the encircling hoop may also be utilized to anchor or mount the assembly in a radiator shell. For this purpose there may be provided on the straps 5 and 6 rearwardly and outwardly extending ears or feet 15 for attachment as by means of screws or studs 16 to the rear edge of an ornamental shell or casing 17, which is supported by the strap 18 riveted or otherwise secured as at 19 to the shell and passing beneath the lower tank 2. A pair of studs or bolts 20 connect the strap 18 with a support or chassis frame member 21, whereby the shell is mounted on the frame and in turn supports through the anchorage hoop the heat radiating unit. To steady the unit in the shell, the lower strap 7 of the hoop may be provided with projection or feet 22 for insertion beneath the heads of the fastening studs 20.

While the above description has been more or less specific as to structural details, it is to be understood that the invention is not limited to the exact details described, but that such modifications may be made as come within the scope of the appended claims.

I claim:

1. In a radiator structure, the combination with an assembly of a heat radiating unit and headers therefor, of a band surrounding the assembly and having interengaging inclined surfaces movable one on the other to contract the band and means to prevent the disengagement of said inclined surfaces.

2. In a radiator structure, the combination with an assembly of a heat radiating unit and headers therefor, of a band surrounding the assembly and wedge means associated with

the band to vary its size and a lock for holding said wedge in adjusted position.

3. In a radiator structure, the combination with an assembly of a heat radiating unit and headers therefor, of a band surrounding the assembly and having reversely bent flanges at adjacent ends nested one within the other, and means to prevent relative movement and disengagement of the flanges.

4. In a radiator structure, the combination with an assembly of a heat radiating unit and headers therefor, of a band surrounding the assembly and having adjacent end portions reversely bent on an incline and nested in wedging relation and means to hold said portions against disengagement.

5. In a radiator structure, the combination with an assembly of a heat radiating unit and headers therefor, of a band surrounding the assembly and having adjacent end portions reversely bent on an incline and nested in wedging relation, one of said portions projecting laterally beyond the other for deformation to prevent their disengagement.

6. In a radiator structure, the combination with an assembly of a heat radiating unit and headers therefor, of a band surrounding the assembly and having adjacent end portions reversely bent on an incline and nested in wedging relation and an ear associated with one portion adjacent the base of the incline which is bendable subsequent to the wedging engagement of said portions to prevent their disengagement.

7. In a radiator structure, the combination with an assembly of a heat radiating unit and headers therefor, of a band surrounding the assembly and inclined channel portions at adjacent ends of the band adapted for nested wedging engagement, the lower part of one channel portion projecting beyond the other and adapted for deformation to close the channel subsequent to the interengagement of said portions to prevent their disengagement.

8. An interlock between adjacent ends of straps or the like including an inclined channel portion on each end adapted for internested wedging engagement, and an end tab associated with one channel portion which is bendable to close the channel.

9. An interlock between adjacent ends of straps or the like, including a reversely bent inclined portion on each end, the two portions being adapted for internested wedged engagement and an end tab on one of said portions bendable to hold the portions in wedged engagement.

In testimony whereof I affix my signature.

JAMES A. WHITE.
